(57) **CLAIM**

The ornamental design of the combined food jar and lid with side lifting handles, as shown and described.

DESCRIPTION

FIG. 1 is a perspective view taken from the upper, front, right-hand side of the combined food jar and lid with side lifting handles of the present invention;

FIG. 2 is a perspective view taken from the lower, back, left-hand side of the combined food jar and lid with side lifting handles of FIG. 1;

FIG. 3 is a side elevational view of the left side of the combined food jar and lid with side lifting handles of FIG. 1;

FIG. 4 is a front elevational view of the food jar and lid with side lifting handles of FIG. 1;

FIG. 5 is a side elevational view of the right side of the combined food jar and lid with side lifting handles of FIG. 1;

FIG. 6 is a rear elevational view of the combined food jar and lid with side lifting handles of FIG. 1;

FIG. 7 is a top plan view of the combined food jar and lid with side lifting handles of FIG. 1; and,

FIG. 8 is a bottom plan view of the combined food jar and lid with side lifting handles of FIG. 1.
